ABSTRACT

Comminuting apparatus includes a grinding drum, means for rotating the drum, grinding teeth mounted within the drum and a stationary grinding device extending into the drum and having complementary grinding surfaces coactive with the teeth. The drum is in the form of a rotor having a perforated peripheral wall through which comminuted material is centrifugally displaced into a chamber about the same, with impeller means on the rotor about the periphery thereof for creating a suction of air outwardly from within the rotor in the comminuting rotation of the rotor. Means are provided for automatically stopping the rotor when a foreign metal particle lodges across a gap between conductive surfaces connected to the rotor and the housing.

COMMUNTING APPARATUS

This application is a division of my application Ser. No. 808,250 filed Mar. 18, 1969, now U.S. Pat. No. 3,617,005, issued Nov. 2, 1971.

The present invention relates to communiting apparatus and is more particularly concerned with such apparatus especially useful in grinding of excess or scrap material trimmed from or resulting from scrapping of molded articles for reuse of the material.

In the mass production of thermoplastic articles, whether blow molded such as bottles or injection molded, as is common with respect to other types of articles, a significant amount of scrap material accrues from trimming from the articles of flash, sprues, connectors, and the like, and from defective or otherwise unwanted articles. Desirably such scrap should be reused, but at least a substantial percentage may be of too large size to be used efficiently with finely divided, pelletized or ground virgin material employed in the molding process, and should be reground.

Heretofore, grinding apparatus suitable for the purpose of efficiently grinding the scrap material, and, where desirable, adding virgin ground or palletized plastic material to the ground scrap material for use of the commingled reconditioned scrap material and the virgin material in a thermoplastic article making machine, has been complex and costly.

It is to the solution of the problems, deficiencies, inefficiencies, disadvantages, defects and shortcomings in prior structures that the present invention is addressed, with the obtainment of important advantages and improvements in communiting apparatus as will be hereinafter more particularly described.

An important object of the invention is to provide new and improved communiting apparatus for thermoplastic material.

Another object of the invention is to provide new and improved communiting apparatus having novel especially efficient grinding means.

Another object of the invention is to provide new and improved communiting apparatus including especially efficient means for moving the comminuted material from the communiting rotor.

Still another object of the invention is to provide new and improved communiting apparatus having novel safety means against lodging of a foreign metal particle.

Other objects, features and advantages of the present invention will be readily apparent from the following detailed description of a preferred embodiment thereof taken in conjunction with the accompanying drawings, in which:

FIG. 1 is a schematic illustration of an apparatus system embodying features of the invention;

FIG. 2 is a perspective view of the thermoplastic communiting and mixing apparatus, with control means shown schematically;

FIG. 3 is an inside face view of the communiting and mixing apparatus;

FIG. 4 is a similar view with the front face plate removed;

FIG. 5 is a perspective view of the rotor of the apparatus; and

FIG. 6 is an enlarged transverse sectional detail view taken substantially along the line VI—VI of FIG. 3.

In the schematic illustration of FIG. 1, thermoplastic material 10 in finely divided state is contained in a

supply hopper 11 from which it is fed to any suitable molding apparatus 12, including blow molding or injection molding having the usual plasticizing and extruder means associated therewith, to produce molded articles

13. For illustrative purposes, the articles are shown as bottles connected by tabs 14 end-to-end to enable convenient handling of the molded string of bottle blanks and delivery of the same to trimming and finishing apparatus 15, the bottle blanks 13 are separated by trimming off the connecting tabs 14, and the blanks are further trimmed and finished as by sizing and reaming the neck or mouth portions of the bottles, whereafter the finished bottles are ejected as for example onto a take-off conveyor or chute 17.

Excess material trimmed off as scrap from the bottle blanks is comminuted to the desired finely divided state for reuse, has added thereto and commingled therewith finely divided virgin material to make up for the

amount of material remaining in the trimmed articles, and the mixture of reground and virgin material is delivered to the supply hopper 11. For this purpose, a combination communiting and mixing apparatus 18 is positioned to receive the trimmings from the apparatus

15 and grind any pieces that are larger than desired. The finely divided virgin material 19 contained in a replenishing hopper 20 is charged through a duct 21 under the control of charging means 22 in the form of a plunger at the outlet from the hopper 20, corelated with operation of the trimming and finishing apparatus 15 to effect a substantially balanced loading of the apparatus 18 with trimmings and virgin material. Within the apparatus 18 the ground scrap material and make-up virgin material is thoroughly commingled and the mixture is delivered through a suitable duct 23 to the supply hopper 11. Desirably, the plastic material conditioning apparatus 18 comprises a self-contained unit

which can be operatively assembled with the apparatus 15 and disassembled as desired for servicing convenience. To this end, the unit 18 is mounted on suitable casters 24 (FIGS. 2,3 and 4) so that it can be wheeled into and out of position with respect to apparatus 15 without requiring any hoisting or lifting assistance. To accommodate the conditioning apparatus 18, a housing wall panel 25 (FIGS. 2 and 6) of the apparatus 15 has a suitable opening 27 therein with means inside the housing such as a chute 28 arranged to deliver plastic trimmings through the opening 27 into and through a receiving opening 29 registering therewith in an inner circular face plate 30 of the apparatus 18 confronting the cabinet or housing wall 25.

For dust-free connection between the wall 25 and the panel 30, a gasket 31 may be interposed therebetween and position of the unit 18 is maintained as by means of the removable screws 32 which extend through an annular lateral flange 33 of a housing 34 of the unit and through the margin of the plate 30 into retaining, clamping threaded or bolted engagement with the wall 25. Primary attachment of the plate 30 to the flange 33 is by means of removable screws 35.

Plastic conditioning is effected within a circular working chamber 37 in the housing 34 by means of a combination communiting, mixing and impeller rotor 38 of generally cup shape having its cavity receptively aligned with the opening 29 and provided with a hub 39 attached as by means of a keyed gripping bushing 40 to

an end portion of a driving shaft 41 mounted on an anti-friction bearings rotatably in a shaft barrel 43 extending outwardly coaxially from the outer end of the housing 34 and either containing a drive motor, or, as shown, mounting thereon an electrical drive motor 44 having its drive shaft suitably connected with the rotor shaft 41 as by means of an endless flexible transmission element such as a belt 45 and suitable transmission pulleys.

Means are provided within the cavity of the rotor 38 for comminuting any pieces of plastic which are of larger than desired size and for ejecting from the rotor all pieces of plastic which are of small enough size whether or not comminution of the pieces has been necessary. To this end, the rotor has at the mouth of its cavity an inwardly beveled annular receiving lip flange 47 which directs material delivered through the opening 29 in the stationary plate 30 to an inner desirably cylindrical drum surface of the rotor which preferably has a replaceable wear ring liner 48 mounted thereon. Rotory driving of the rotor 38 is preferably at a high speed such as on the order of 2,400 rpm such that particles of plastic which are of suitable small size will be ejected centrifugally through several, in this instance three, staggered annular axially spaced rows of gaging holes 49 in the liner 48 aligned with respective discharge holes 50 in the annular wall of the rotor.

Pieces of plastic which are not small enough to escape through the holes 49 are comminuted by means of cutter teeth 51 and 52 disposed at suitable circumferential positions such as quadrantly and in two axially spaced rows, removably locked as by means of set screws 53 and 54, respectively, in radial respective sockets 55 and 57 in the rotor drum wall and with suitably shaped cutter bit ends projecting inwardly from the liner 48, and grindingly or comminutingly cooperative with a cutter block 58. This block is fixedly mounted on the inner side of the face plate 30 below the opening 29 which is provided with a horizontal inwardly beveled lower edge 29a substantially above the block 58 to provide in the lower portion of the rotor cavity a substantial material receptacle.

In a desirable form, the block 58 is a substantially rectangular piece of metal secured by means comprising a pair of attachment bolts 59 and 60 to the inner face of the plate 30 below the edge 29a which is located adjacent to and parallel with a horizontal median plane across the comminuting cavity of the rotor 38 whereby to provide with the lower portion of the cavity a substantial plastic trimmings receiving receptacle within which the block 58 is coactive with the teeth of the bits 51 and 52. In size the block 58 is proportioned to fit in closely spaced relation to the confronting surfaces within the grinding drum cavity of the rotor, as best seen in FIG. 6, namely, the inner radial wall surface, the surface of the lip flange 47, and the surface of the liner 48. This spacing is close enough to avoid large pieces from escaping past the block while fines may pass freely thereby in the rotation of the drum without gumming up due to relative passing frictional pressure.

Efficient grinding coaction between the grinding teeth and the block 58 is effected by having the block mounted within one end facing in opposition to the direction of rotation of the drum and head on to the plastic pieces in the lowest sector or pit within the

drum. By its length and up-tilted disposition within the drum in the direction of rotation, the head-on end face of the block is disposed at a diagonal angle converging with the surface of the liner 48 (FIG. 3) such that a grinding throat is provided leading to the lower corner of the block which is provided with grinding grooves 61 complementary to the grinding teeth and with the groove surfaces in closely spaced relation to the side contours of the teeth so as to comminute the plastic pieces as the teeth run through the grinding grooves in the high speed rotation of the drum. By having the grooves 61 only in the lower corner portion of the block 58, and the lower edge face of the block extending in divergent progressively widening gap relation to the confronting liner perimeter relatively free movement of plastic particles onward from the grooves avoids jam-up but enables agitation of the particles as they are advanced to a second stage grinding coaction between the block and the teeth, as the teeth pass through complementary grinding grooves 62, substantially the same as the grooves 61 but located in the remaining lower, trailing corner of the block with the lower face of the block converging toward such grooves and the drum liner surface. In this two-stage grinding to which the plastic pieces are subjected, extremely high speed, efficient comminution is effected. To secure the most effective grinding setting of the block 58 relative to the grinding teeth, the block is adjustably mounted, with at least the bolt 60 adjacent the head end of the block extending through an adjustment slot or adjustment clearance opening 63 in the plate 30, with a heavy washer 64 bridging the opening. In the high speed rotation of the grinding drum, all particles of small enough size are ejected centrifugally through the gaging holes 49 in the liner and the exit holes 50 in the rotor 38 into a substantial clearance about the rotor within the chamber 37.

To assist in ejection of the comminuted particles and fines from the grinding drum, and to evacuate the chamber 37, the rotor 38 is equipped with impeller fan means comprising a circumferentially spaced series of radial impeller vanes 65 mounted rigidly on the perimeter of the rotor and having a central reinforcing ring 67 rigidly connecting the outer margins of the vanes (FIGS. 4, 5 and 6). Thereby, air is drawn in through the grinding drum holes 49 through the aligned openings 27 and 29 from within the housing of the machine 15 not only to assist in evacuating the drum of comminuted particles and fines, but also to accelerate delivery of trimmings into the drum and to evacuate the machine cabinet of plastic dust that may develop in the trimming and finishing of the plastic articles. From the chamber 37 the plastic particles are driven by the impeller into the duct 23 by which the reground material is delivered to the extruder hopper 11.

In addition to its blower function, the grinder-impeller drum 38 also functions to mix the charges of virgin material delivered from the hopper 20 through the duct 21 with the reground material. To this end, a lower discharge end of the duct 21 extends downwardly and inwardly through a supporting flange 68 at the forward end of the barrel 43, with its discharge end directed through a central opening 69 in the back of the housing 34 generally toward the hub 39. As the material drops from the discharge mouth of the duct

21, it is caught in radially outwardly extending distribution channels 70 (FIGS. 5 and 6) along the back of the rotor 38 and centrifugally propelled from the perimeter of the rotor in between the impeller vanes 65. Desirably there is one of the distribution channels 70 for each space between impeller vanes. Each of the channels desirably has a smaller inner, material receiving blind end portion 71 which leads into a substantially wider remaining portion of the channel which opens through the perimeter of the rotor. Thereby fairly uniform commingling of the virgin material with the reground material is attained, and the mixture propelled from the unit through a tangential opening 72 (FIG. 4) in the cylindrical wall of the housing 34 leading into a generally tangential discharge nozzle 73 to which the delivery duct 23 is connected.

In order to facilitate the propelling and mixing action of the channels 70, means are provided for indrawing of air by the impeller in the direction of movement of the virgin material charged into the housing. Conveniently this is accomplished by providing a spaced relation between the flange 68 and the back of the housing 34, at least in the vicinity of the charger duct 21. Accordingly, a spacer block 74 (FIG. 6) is disposed between the flange 68 and the housing along the lower portion of the joint and has an inner edge curved substantially complementary to the adjacent edge of the opening 69 so that any material dropping onto the curved surface of the spacer will readily enter through the opening. This spacer is of limited segmental form so as to leave substantial gap area through preferably greater than 180° between the flange 68 and the housing 34 beyond the ends of the segmental spacer. A plurality of bolts 75 secure the flange 68 to the housing 34 with the spacer 74 clamped therebetween and with small spacer blocks 77 located at the bolts beyond the spacer 74. To prevent inadvertent escape of any of the plastic particles and to prevent entrance of undesirable foreign material, a screen 78 is mounted over the air entry gap. Through this arrangement, it will be apparent that air may be drawn in by the fan action of the impeller through the screened gap at the back of the housing 34 and more particularly in the region of the discharge and of the charging duct 21, with a desirable eduction across the mouth of the duct to enhance movement of the material therefrom into the working chamber 37.

Means are provided for controlling operation of the virgin material charging apparatus in coordination with the trimming and sizing apparatus 15 and with the operation of the unit 18. Accordingly, the charging plunger 22 is operated by a piston rod 79 of an actuator including a cylinder 80, and desirably driven pneumatically to reciprocate the plunger 22. Compressed air for driving the actuator 80 is supplied through conduits 81 leading from a control valve 82 which is operated by a reciprocating cam 83 driven by suitable mechanism within the apparatus 15 coordinated with the trimming of each article therein. Thereby a make-up charge of granular virgin material is adapted to be rammed from the hopper 20 into the make-up duct 21 for each article processed in the apparatus 15. However, this should occur only while the grinder-impeller rotor 38 is operating. Therefore the air supply line 81 is controlled by a solenoid valve 84 to be opened only when the

motor 44 is running. For this, the operating solenoid for the valve 84 is connected into electrical control circuitry 85 for the motor and which includes a control switch 87 which upon being closed energizes the motor control circuit through a relay 88 closing suitable contacts while the control switch is closed. Thereby, coincident with energizing, the valve 84 is opened to activate the air supply line for the actuator 80.

To avoid overloading the supply hopper 11, a normally closed safety switch 89 is mounted therein at a maximum load height and additional material opens the switch to break the connecting circuit to the solenoid for the air line valve 84 so that this valve then closes and the actuator 80 is inactivated even though the control valve 82 may continue to function so that any other devices that may be controlled thereby will continue to function. Automatically upon sinking of the level of material in the hopper 11 below the maximum level, resumption of replenishing virgin material charging of the unit 18 results. Sometimes metallic particles of a size that might be damaging to the high speed rotor and grinding members may be delivered with the trimmings or even with the virgin material. Therefore, safety shut-down means are provided, conveniently comprising an electrically grounded connection 90 to the housing 34 leading from a solenoid 91 connected to a normally closed switch 92 in the energizing circuit for the relay 88. The other end of the safety circuit 90 is grounded to the motor casing 44 and the barrel 43, the latter being electrically insulated from the housing 34 by having the spacers 74 and 77 of a dielectric material such as bakelite. The screen 78 may be made from a dielectric, plastic material or suitably insulated from either the flange 68 or the housing 34. Also, the washers 93 are of an electrically insulating material. Hence, the safety switch 92 remains closed until a metal particle lodges between the rotor 38 and the cutter block 58 whereupon an electrical circuit is completed through the circuit 90, the solenoid 91 energized and the switch 92 opened, the relay 88 deenergized, the motor 44 stopped to stop the rotor, and the solenoid valve 84 closed to stop operation of the actuator 80. The offending metallic particle can then be removed and the apparatus restarted.

An advantage of grinding the thermoplastic scrap immediately as it accrues is that moisture absorption is at least minimized, and avoided where the scrap is still possessed of substantial residual molding heat (which may be as much as 200° F. with some materials).

Where different, combined, selective and like color or material combination effects are desired in the produced articles, a plurality of the virgin material hoppers 20 and charge metering devices 22 may be provided in battery or selective orientation to feed their particular contents through a common duct or individually to the unit 18.

Any suitable covering and dust eliminating means may be used in conjunction with the supply hopper 11 as desired or needed.

It will be understood that variations and modifications may be effected without departing from the spirit and scope of the novel concepts of this invention.

I claim as my invention:

1. Commuting apparatus of the character described comprising:
a grinding drum;

means for rotating said drum;
grinding teeth mounted within said drum; and
a stationary grinding device extending into said drum
and having complementary grinding surfaces coac-
tive with the teeth.

2. Apparatus according to claim 1, said stationary
grinding device cooperating with said teeth to provide
two successive grinding stages along the drum.

3. Apparatus according to claim 2, in which said sta-
tionary grinding device comprises a block, said block
having successive surfaces converging toward said
drum, and grinding grooves extending through the
respective ends of said surfaces nearest the drum and
cooperating with said grinding teeth to provide said two
successive grinding stages.

4. Apparatus according to claim 1, in which said
grinding drum has a cavity provided with a cylindrical
perforated wall, and said teeth project inwardly on said
wall.

5. Apparatus according to claim 4, wherein said wall
has a liner on its cavity surface, said liner having gaug-
ing holes therethrough aligned with larger clearance
perforations through said wall and said teeth project
through said liner into the cavity.

6. Apparatus according to claim 4, in which said
grinding device comprises a block supported stationarily
in said cavity in cooperative relation to said cylindri-
cal wall and said teeth, said block having complemen-
tary grinding grooves providing said grinding surfaces
and receptive of said teeth in the rotation of the drum.

7. Apparatus according to claim 6, including means
for adjusting said block relative to said wall and teeth.

8. Apparatus according to claim 6, said block having
a surface convergently related to said cylindrical wall in
the direction of rotation of the drum to provide with
said wall a material guiding throat leading toward said
grooves.

9. Comminuting apparatus of the character
described comprising:

a housing providing a working chamber;
a rotor having a cavity therein into which material to
be comminuted is adapted to be delivered;
means within said rotor for comminuting material
delivered into the cavity;
said rotor having a perforated peripheral wall
through which comminuted material is centrifu-
gally displaced into the chamber from the cavity in
the comminuting rotation of the rotor; and
impeller means on and about the periphery of said
rotor for creating a suction of air outwardly from
within the rotor in the comminuting rotation of the
rotor.

10. Apparatus according to claim 9, including
generally radial grooves on said rotor outside of said
cavity, and means for delivering additional material to
said grooves for centrifugal commingling with the com-
minuted material in said chamber.

11. Apparatus according to claim 10, including air

passage means into said housing adjacent to said means
delivering material to enable movement of air by the
impeller means from said passage means and along said
grooves to enhance material-comingling action through
the rotor grooves.

12. Apparatus according to claim 1, including a
housing providing a working chamber for said drum, an
electrical drive motor operatively connected to said
drum and comprising said means for rotating the drum,
and means operative in response to closing of an elec-
trical circuit including said drum and said housing by
lodging of a foreign metal particle across a normally
open gap between respective electrically conductive
surfaces connected to the drum and to the housing to
stop said motor.

13. Apparatus according to claim 12, including
means operative to deliver material to said drum and
comprising electrically motivated operating means,
said means for stopping said motor by lodging of a
foreign metal particle across said normally open gap
being also operative to stop said material delivering
means when the motor is stopped.

14. Comminuting apparatus according to claim 9, in-
cluding, an electrical drive motor operatively con-
nected to said rotor; and

means operative in response to closing of an elec-
trical circuit including said rotor and said housing by
lodging of a foreign metal particle across a nor-
mally open gap between respective electrically
conductive surfaces connected to the rotor and to
the housing to stop said motor.

15. Apparatus according to claim 14, including
means operative to deliver material to said comminut-
ing means and comprising electrically motivated
operating means, said means for stopping said motor by
lodging of a foreign metal particle across said normally
open gap being also operative to stop said material
delivering means when the motor is stopped.

16. Comminuting apparatus of the character
described comprising:

a housing providing a chamber;
means within said housing for comminuting material
including a rotor;
an electrical drive motor operatively connected to
said rotor; and
means operative in response to closing of an elec-
trical circuit including said rotor and said housing by
lodging of a foreign metal particle across a nor-
mally open gap between respective electrically
conductive surfaces connected to the rotor and to
the housing to stop said motor.

17. Apparatus according to claim 16, including
means operative to deliver material to said comminut-
ing means and comprising electrically motivated
operating means, said means for stopping said motor by
lodging of a foreign metal particle across said normally
open gap being also operative to stop said material
delivering means when the motor is stopped.
